PACKING MACHINE FOR FLATTENED OR
OVAL CIGARETTESJohannes Neff, Dresden, Germany, assignor to
the firm "Universelle" Cigarettenmaschinen-
Fabrik J. C. Müller & Co., Dresden, GermanyApplication May 5, 1930, Serial No. 449,822
In Germany January 9, 1930

1 Claim. (Cl. 226—5)

In the usual cigarette packets for flattened or oval cigarettes it is desirable that the uppermost layer should show a quite uniform position of the cigarettes with all the imprints facing upwards but this is not the case with the lower layers. Methods and apparatus for obtaining this uniform position of flattened or oval cigarettes are described for example in German Patent 430,311 and in U. S. patent application, Serial

10 Number 302,984, now U. S. Patent No. 1,812,294.

As uniform position of the cigarettes in the upper layer only is desired and not in the lower layer or layers which amount to at least one half and often two thirds of the number in a packet, 15 in accordance with the present invention, not all of the cigarettes to be supplied to a packet are properly arranged. Thus the cigarettes forming the uppermost layer and those forming the lower layer or layers are subjected to different treatment. Hitherto however the cigarettes which did not require to be treated were guided in the same direction as the upper layer of the main feed track which was of disadvantage to the cigarettes inasmuch as they were liable to 20 be damaged. Moreover it was not economical since the need for adjacent tracks made the machines too large, a matter of considerable importance in machines having two or three rows of packets.

30 In accordance with the invention these disadvantages are avoided and damage to the cigarettes reduced to a minimum by supplying the cigarettes not to be treated direct from a container to the feed track so that a repeated separation and transport of the cigarettes at least in those layers is avoided.

First the cigarettes serving to form the lower layers are removed in known manner in a single or double layer (or in certain cases in even greater numbers of layers) by a channel shaped slide from a pile in which the cigarettes are located in separate vertical rows separated by partition walls. The slide feeds the group of cigarettes removed from the pile on to a feed track on which or by which the group of cigarettes is fed in the direction of the longitudinal axis of the cigarettes to the packing station. Transversely of this primary feed means extends a pocket band such as described in said U. S. patent application, Serial Number 302,984 which feeds the cigarettes removed from the pockets through a directing device described therein. Where this pocket band meets the first mentioned feed means is arranged a guide surface extending thereover and over which a gripper device

grips in groups the cigarettes fed to it by the pocket band and directed therein to form the upper layer and over the first mentioned group (forming the lower layer) which are passed by the feed means in the meantime to the transferring station. Suitable means strip the group forming the upper layer from the said guide surfaces in the direction of the primary feed means supplying the lower group of cigarettes so that this feed means can now feed all the cigarettes necessary to fill the packet with the cigarettes forming the upper layer in the correct position.

Such a packing means is illustrated in the accompanying drawings, the illustration being limited to the parts necessary to facilitate an understanding of the invention which are mostly well known.

Fig. 1 is a plan of the whole arrangement, Fig. 1a is an enlarged view of a detail, Fig. 2, a vertical section on the line I—I of Fig. 1, and Fig. 3, a section on the line II—II of Fig. 1.

Referring to the drawings, 1 denotes the container which is rectangular in plan and is hopper-shaped in elevation its lower part being divided by the vertical partition walls 2 into narrow pockets each adapted to receive a vertical row of cigarettes. Beneath this container moves a slide 3 formed with slots corresponding to the division walls 2 by which the lowermost layer of cigarettes is fed over the guide surface of the primary feed track. This track consists of a sheet metal base 5 between sides 6 and a band 8 running above the base 5 and passing over roller 7, said band being provided with entraining members 9 located at suitable distances apart. The entraining members each consist of two fingers with a slot between them. The feed means described feeds the layer of cigarettes 2 brought from the slide 3 into the path of the entraining members 9 in the direction of the arrow to the 85 packing station.

Transversely of the primary feed track is arranged the secondary feed track for the cigarettes intended to form the upper layer, such secondary feed track being in the form of a band 10 having pockets, which band runs over the pulleys 11 and 12. It travels from beneath the container 14 the shape of which is generally similar to that of the container 1. At the lower end of this container are also disposed vertical partition walls 14 by which the cigarettes in this portion are separated into vertical rows. There are thus located in the lower part of the slots formed by the partition walls hinged flaps 15 and beneath the end faces of the container a grid like slide 16. 110

The members 15 and 16 move alternately into the open position and thus form a kind of sluice through which only one cigarette is allowed to pass from each vertical row. The pocket band 10 then passes to a directing device 17 such as is described in said U. S. patent application, Serial Number 302,984. Where the band 10 meets the primary feed track a shaped guide surface 18 is provided, which with its forked portion extending into the path of the band 10 engages beneath the ends of the cigarettes projecting beyond the pockets. The lower platform shaped part of the guide surface 18 extends over the base 5 of the feed tracks 5, 6 at such a level that the group of cigarettes z can pass beneath the guide surface. Over the guide surface moves the rotating cross 19 which carries a group of cigarettes s serving to form the upper layer from the pockets and pushes them towards the end of the guide surface 18. This operation coincides with the continuous movement of the primary feed track so that the group of cigarettes s meets the group z . When the next entraining member 9 comes forward it pushes forwards with its lower finger the group z and also with its upper finger the group s and thus guides the total number of cigarettes required for the packet with those of the upper layer properly arranged to the packing station. The track 5, 6 which is U-shaped has one of

its side walls 6 (the one adapted to face the pocket band 10) recessed as at 6' through which extends the platform 18. The forked portion 18' of said platform which extends into the path of the band 10 and is adapted to engage the ends of the cigarettes 5 carried by said band, is also recessed as at 18' to permit the passage of the members of the revolving cross 19. The entraining members 9 of the band 8 are slotted and project laterally from the band 8 so that they can pass through the track 5-6.

I claim:

A packing machine for flattened cigarettes comprising a container for the cigarettes of the lower layers, said container adapted to hold the cigarettes in vertical rows, a slide for ejecting them from the container, a primary feed track on to which they are ejected by said slide and by which they are fed in the direction of their longitudinal axes to the packing station, a container for the cigarettes intended to form the upper layer, a pocket conveyor receiving the cigarettes from said container and extending transversely of the primary feed track, and means for correcting the position of the cigarettes intended to form the upper layer before they reach the primary feed track and means associated with the primary feed track for feeding both layers to the packing station.
